UNITED STATES PATENT OFFICE.

JOHN B. LACY, OF CHICAGO, ILLINOIS.

REFRIGERATION SYSTEM.

1,404,531.

Specification of Letters Patent. Patented Jan. 24, 1922.

Application filed December 20, 1920. Serial No. 431,973.

To all whom it may concern:

Be it known that I, JOHN B. LACY, a subject of the King of England, and a resident of the city of Chicago, in the county of Cook and State of Illinois, have invented a new and useful Improvement in Refrigerating Systems, of which the following is a full, clear, and exact description.

My invention relates to improvements in refrigerating systems, and it consists in the combinations, constructions and arrangements herein described and claimed.

The present invention is designed to be an improvement over that set forth in my prior Patent No. 1271482 dated July 2, 1918. In said prior patent, means was disclosed for producing a circulation of air in rooms provided with refrigerating coils. The present invention is applicable to refrigerating systems of this type, but is directed to several features not contemplated by the prior patent.

An object of my invention is to provide a system of the type mentioned, having means for controlling the humidity or the relative amount of moisture in the air of the room to be cooled.

A further object of my invention is to provide a system of the type described, in which the air may be purified or freed from obnoxious odors or gases.

A further object of my invention is to provide a device by means of which a circulation of air may be maintained within the room which is cooled by cooling coils or pipes, these means consisting of partitions spaced from the pipes and terminating short of the top and bottom of the room, whereby a current of air is caused to pass downwardly over the pipes and behind the partition, and upwardly in front of the partition, means being provided for giving ready access to the cooling pipes, so as to remove the frost deposited thereon, or for inspecting the pipes, or to make repairs.

Other objects and advantages will appear in the following specification, and the novel features of the invention will be particularly pointed out in the appended claim.

My invention is illustrated in the accompanying drawings, forming part of this application, in which—

Figure 1 is a front view of a portion of a cooling room provided with one embodiment of my invention.

Figure 2 is a vertical section through the device,

Figure 3 is a detail view showing a door mounting,

Figure 4 is a sectional view through the 60 slidable door construction at right angles to Figure 3,

Figure 5 is a detail view showing means for securing the partitions in place,

Figure 6 is a detail view showing the lower 65 damper and the means for regulating the same,

Figure 7 is a detail view showing a portion of the upper damper and means for regulating the same,

Figure 8 is a sectional view through a 70 modified form of the device as applied to overhead coils,

Figure 9 is an enlarged section along the line 9—9 of Figure 8,

Figure 10 is an enlarged section of a portion of the device shown in Figure 8, and

Figure 11 is an edge view of the upper damper shown in Figure 8.

Referring now to the drawings, I have 80 shown therein a partition including uprights like that shown at 12 in Figures 1 and 2, these uprights having laterally extending foot portions 13 and also laterally extending cap portions 14. The uprights 85 12 are provided at the ends of the sections of the partition. A description of one, therefore, will suffice for all. The foot portion 13 acts as a spacing member, and is placed with its end abutting the wall 15. The cap 90 portion 14 is provided with set screws 16 which are arranged to bear on a plate 17 placed in contact with the ceiling 18 of the room. By tightening up on the set screws 16, the uprights 12 are held rigidly in position, without the necessity of using fastening devices which penetrate the ceiling, the walls, or the floor. The set screws may be set to hold the device rigidly and locked in its holding position by lock nuts, such 95 as that shown at 19 in Figure 5.

Secured to the uprights 12 are lower brackets or braces, such as that shown at 20 in Figure 4. A bolt 21 passes through a pair of track rails 22 and 23, which are 105 spaced apart from each other by a collar or sleeve 24 which surrounds the bolt, one of the track rails being spaced from the upright 12 by a sleeve 25, the ends of the bolt being passed through a flange 12, of 110

- the upright, and being held in position by means of a nut 26. This construction provides rigid tracks which are parallel with the wall 15.
- 5 An upper door guiding means 27 is provided by bending a piece of sheet metal back upon itself to constitute guide grooves 28 and 29, in which doors or panels 30 and 31 respectively are arranged to slide. It will be noted 10 that the upper part of the member 27 is slightly inclined, and that a bolt 32 secures the member 27 to the flange 12_a of the upright 12. The lower portion of each panel is provided with rollers 33, which are set into 15 recesses and which bear upon the track rails 22 and 23, as clearly shown in the drawing. It will thus be seen that a partition is formed, consisting of a series of doors or sliding panels, any one of which may be moved relatively 20 to the adjacent door or panel to permit access to the pipes 34, which are disposed between the partition and the wall 15, as shown in Figure 2.
- Pivottally mounted at 35 on the guide member 27 is a draft regulator or damper which 25 consists of a flat plate 36. This damper is shown as fully open in Figure 2, but it may be swung upwardly toward the ceiling, and is held in adjusted positions by means of an 30 inclined bar 37 which is rigidly secured at one end to the upright 12. As will be seen from Figure 7, a removable pin or bolt 38 may be placed in openings 39 in the bar 37 to hold the damper 36 in its adjusted positions.
- 35 In the space underneath the cooling pipes 34 is a damper 40 which is hinged at 41 to a bar 42 carried by the foot piece 13. The free end of the damper 40 is connected by a pivoted arm 43, whose lower end is adapted to 40 receive a bolt or pin 44 which may be placed in any of the openings 45 in the bar 42 to support the damper in any of its adjusted positions. This damper may be swung upwardly, 45 as shown in dotted lines in Figure 7, so as to close off the bottom of the space behind the partition completely, or it may be placed so that the damper will be inclined, to cause a forward movement of the air descending between the partition and the wall, as will be 50 explained later.
- From the foregoing description of the various parts of the device, the operation thereof 55 may be readily understood. In my prior patent, I disclosed a device of the same general nature, but with no means for closing off the space between the partition and the wall, for permitting access to the pipes. The pipes 34 are cooled in any suitable manner, and the air in the immediate vicinity is 60 chilled and tends to condense and pass downwardly due to its greater density. This causes a circulation of the air from the center of the room above the partition, and downwardly over the cooling pipes. By regulating 65 the distance of the free end of the upper
- damper 36 from the ceiling, the velocity of the air may be controlled. I have found however that by adjusting the lower damper 40 the humidity, or the relative amount of moisture in the air, may also be controlled. 70 When the lower damper is closed, or very nearly so, thus slowing up the current of air passing the coils, the humidity in the room will be greater than when the lower damper is open to permit a free flow of the cooled air 75 from behind the partition, underneath the same, into the room. When the lower damper is closed entirely, the cooled air surrounding the pipes appears to bank up and flow over the top of the partition, the moisture laden air depositing its moisture on the ceiling. In actual practice of course, it is not desirable to do this, but the lower damper may be so regulated as to increase or decrease the humidity to any desired points within limits. For certain articles a more humid atmosphere is necessary, while for others, a drier atmosphere is necessary, and by regulating the lower damper the humidity may be controlled. 85
- I have also found that while the warmer portion of the air current, i. e., that passing over the top of the partition, may contain foul air and odors, the cooled air coming from underneath the partition is relatively 90 pure. This purification appears to be in the nature of a physical change, and is probably due to the absorption of noxious vapors and gases by the water of condensation. It has been found by experiment that noxious 95 fumes, such as those from the plumber's charcoal furnace, may be removed from the air, and the latter rendered comparatively pure, by the use of the construction which forms the subject of this application, so that the 100 workmen can continue their work in comparative comfort, whereas they were overcome by fumes under similar circumstances, when working in the room having cooling pipes, but not provided with the means for 105 causing the circulation of air.
- One of the objections to the use of partitions heretofore for causing a circulation of air was the fact that these partitions, being usually set close to the pipes, i. e., within 110 twelve inches or so of the wall, prevented the access to the pipes for the purpose of removing the deposit of frost, or access for repairing the pipes when necessary. In the present construction, however, this difficulty is obviated by the use of sliding panels, which may be moved to permit access to any portion of the pipes, and again closed to constitute a partition, which will cause the flow of air in the manner described. This one feature 115 renders the present device especially desirable, since under certain conditions the removal of the frost and the scraping of the pipes is highly desirable. 120
- By my system of air circulation control, 125

- a proper humidity may be attained, and at the same time the deposit of moisture on the pipes may be reduced. In one instance in which my improved system was installed, 5 a refrigerator 10 ft. by 13 ft. by 8 ft. was kept at a temperature of 32 degrees Fahrenheit, and the pipes did not require scraping or defrosting for more than six months after installation.
- 10 In Figure 8 I have shown a vertical section of a cooling room, in which the cooling pipes 46 are disposed at the top of the room, instead of at the side. Below the cooling pipes are rafters, like that shown at 47. 15 These rafters support a partition which consists of sections composed of wood strips 48 and insulating material 49, such as fiber. The sections rest on brackets 50 secured to the rafter 47 (see Figure 9). Above each 20 rafter is a projecting strip consisting of a wood upper portion 51 and an insulating lower portion 52 of fiber or other suitable material. The upper surfaces of the member 51 are protected by a metal sheathing 53, 25 whose edges overlap the upturned edges of drip pans 54 disposed above the partitions and between the rafters. At one end of the partition is disposed a strip 55 which bears U-shaped guides 56 for the lower portions 30 of slidable doors 57 and 58 respectively. The upper portions of these doors are held between guide strips 59 and 60 respectively, carried by pipes or bars 61 and 62 which pass through a plate, such as that shown 35 at 63, at each end. The plate 63 is secured to an arm 64 which is hinged at 65 to a bracket 66, carried by the rafter 47 at each end. This rafter bears an upright 68 which is curved in arcuate form and provided with 40 openings 69. The plate 63 also has an opening 70 through which a pin may be passed. This construction permits the bodily movement of the plates 63 when the pins 70 are withdrawn, the bottoms of the slidable doors 45 pivoting on their guide sockets or grooves 56, so that the space between the wall and the ends of the doors may be adjusted to
- control the air current, and at the same time to permit the doors to slide past one another, so as to afford a good access to the pipes for 50 scraping them or repairing them.
- At 71, I have shown a damper, whose position may be regulated by means of an arm 72 held by a pin in the perforations 73 in the strip 74, similar to that described in connection with Figure 2.
- This form of the device operates substantially the same as that disclosed in Figures 1 and 2. In this particular instance, however, the air entering at the right hand side 60 of Figure 8 passes over the pipes and downwardly on the left hand side, being controlled by the damper 71 which regulates the humidity in the manner already described. By tilting the doors to the proper 65 angle, the space between the doors and the wall may be regulated so as to cause a current of air to flow at the desired velocity over the pipes. The provision of the drip pans above the partition keeps the latter dry, 70 and the water of condensation is conveyed off by means of a gutter 75, or in any other suitable manner.
- I claim:
- In a refrigerating system, a cooling room, 75 cooling pipes disposed therein near one wall, a partition, terminating short of the floor and ceiling of the room to define air passages above and below the partition, between said cooling pipes and the main body portion 80 of the room, said partition comprising vertical supports, each having a channel iron at its lower and upper ends, the lower iron being adapted to rest on the floor and to abut the adjacent wall, a ceiling plate, set screws 85 carried by said upper channel iron and adapted to engage said ceiling plate, whereby each support is held in position, an adjustable damper carried above the partition, and a second adjustable damper disposed below 90 said partition, said dampers being adapted to close the space between said partition and the wall.

JOHN B. LACY.
